CLAIM

The ornamental design for a mobile food cooking trailer, as shown and described.

DESCRIPTION

FIG. 1 is a top, rear and right side perspective view of a mobile food cooking trailer showing my new design; FIG. 2 is a top, front and left side perspective view thereof;

FIG. 3 is a left side elevational view thereof;

FIG. 4 is a top plan view thereof;

FIG. 5 is a right side elevational view thereof;

FIG. 6 is a front elevational view thereof; and,

FIG. 7 is a rear elevational view thereof.

The undisclosed bottom view is plain and unornamented.
